UNITED STATES PATENT OFFICE.

WILLIAM J. WARD, OF NEW ROCHELLE, NEW YORK.

PAPER-CUTTING DEVICE.

No. 818,065.

Specification of Letters Patent.

Patented April 17, 1906.

Application filed November 11, 1904. Serial No. 232,356.

To all whom it may concern:

Be it known that I, WILLIAM J. WARD, a citizen of the United States, residing in the city of New Rochelle, county of Westchester, 5 State of New York, have invented a certain new and useful Paper-Cutting Device, of which the following is a specification.

This invention relates, primarily, to means for severing a web of paper into sheets after the printing of the web and before the folding of the sheets, and is in the nature of an improvement on devices of this class heretofore employed in web perfecting and folding machines, although the invention may be 15 used for other purposes or in other machines.

It is often required to sever a large number of superposed webs or plies of web simultaneously, these plies being assembled before passing between the cutting-cylinders, and 20 hence it is necessary that the teeth project considerably from their cylinder, since each tooth must fully penetrate the most remote 25 ply of paper in order to insure the severing of same by the series of teeth. Owing to this great projection of the teeth, especially where many plies of web are to be punctured, it happens that the position of the teeth (viewed edgewise) when entering the groove in the opposing cylinder is at a considerable angle 30 to their position when emerging from the groove, and the groove consequently is made very wide and ample to avoid contact of the teeth with the sides thereof; but this width of the groove is a great detriment, since the 35 edges of the recess are necessarily so far apart that they do not afford a sufficient support for the web, and the teeth tuck the web into the groove, thereby not only spoiling the register of the sheets, which is a great objection, 40 but also making a jagged cut, which is unsightly and objectionable, besides which there is a constant liability of the web becoming caught and torn, causing a delay for stopping the press, removing the debris, and getting 45 the press into operation again, which is a serious matter, since, for instance, a delay of a few minutes often entails the loss of the sale of almost an entire edition of a newspaper.

The principal objects of my invention are 50 to make a cleaner cut of the paper and to avoid the liability of tucking the web into the groove or of tearing the same.

In carrying out my invention, I preferably employ a cutting-blade provided with teeth 55 of the ordinary kind, each having an inclined

cutting edge, but which are incapable of such projection during the cutting operation that their punctures will unite to form a single continuus cut across the web, and during the penetration of the web by the teeth I contrive to give the teeth a movement longitudinally of the cylinder, so that the teeth not only puncture the paper, but also lengthen the punctures by such endwise movement, which movement is preferably sufficiently great to unite all the punctures, making a single cut. This may be accomplished, although only the tips of the teeth penetrate the web instead of forcing the teeth bodily through the paper, as heretofore, since the longitudinal movement of the teeth compensates for their slight penetration of the paper. Moreover, the tips of the teeth project only a very little into the groove in the opposing cylinder, so that the teeth occupy said groove during a shorter period of the revolution and there is hence less angular movement of the teeth while in the groove. Thus it results that the groove may be made so narrow as to substantially fit the teeth, or, in other words, the edges of the groove may be brought very near together, so that an ample support is given to the web during the severing operation, avoiding liability of tucking the web into the groove or of tearing the web and making a clean unbroken cut the entire width of the web.

In the accompanying drawings, Figure 1 is an end view of a pair of geared cutting and feeding cylinders provided with my improvements. Fig. 2 shows the cylinders seen at Fig. 1, but with the severing-blade in a plane joining the axes of the cylinders, the web-severing teeth penetrating the groove in the opposing cylinder and the cut being done or nearly done. Fig. 3 is a partly sectional side elevation of the cylinders with the parts in the positions seen at Fig. 2. Fig. 3^a is a plan of a fixed groove-cam by which the cutting-teeth are reciprocated. Fig. 4 is an elevation, and Fig. 5 a plan, of a box to hold and guide the reciprocating knife, the box being secured to the cylinder in a well-known manner. Fig. 6 is an end elevation of the box with its appurtenances, including the knife. Fig. 7 is a side elevation of a reciprocating knife-carrying bar mounted within the box. Fig. 8 shows side and end elevations of a spring-pressed cheek block or bar contiguous to the knife for biting the web against the

opposing cylinder during and after the severing operation. Fig. 9 is a sectional end elevation showing how the knife-sections are detachably secured to the reciprocating bar. 5 Fig. 10 shows diagrammatically the projection of an entire tooth through the paper in order to secure a puncture of the requisite length and also for comparison how a puncture or cut of the same or greater length is secured by my invention by projecting only the tip of the tooth through the paper, a large portion of the cut being due to the movement of the tooth across the paper. Fig. 11 gives for comparison two views, one showing the 10 body of a tooth projecting into the opposing groove in the usual manner, the groove being widened, as usual, to accommodate the different angular positions of the knife due to its rotation, and the other shows the slight 15 projection of the tips of the cutting-teeth into the groove due to my invention, as well as the substantial fit of the groove to the teeth. 20

The invention is applied to a pair of cutting and feeding cylinders 1 2, between which 25 runs the single or multiple ply web 3. The upper cylinder 1 is shown of double the diameter of the lower 2 and making one revolution to two of the latter; but obviously the cylinders may be of equal size within the scope of 30 the invention and may be used for other purposes besides cutting and feeding. The cylinders turn in the direction indicated by the arrows, and the web 3 is seen advancing horizontally, although by turning the view quarter-way around it will represent the web moving vertically down. The cylinders are 35 connected by gears 4 5, either of which may be the driver, and are journaled in the usual framework 6 7.

40 Upon the cylinder 2 and extending longitudinally thereof is a knife-box 8, having sides 9 10 and secured to the cylinder by bolts 11. Extending the length of the box is an endwise reciprocatory bar 12, occupying 45 about half the width of the box. To the inner side of this bar are detachably secured blade-sections 13 by means of screws 14, each blade having its outer edge formed with a series of serrations or teeth 15 and the sections being placed end to end, so as to make 50 practically a continuous blade. Cross-pins 16, extending between the walls 9 and fixed therein, fit in longitudinal slots 17, cut in bar 12 and in the blade-sections and prevent the 55 bar and blade from rising. The remainder of the box is occupied by a cheek block or bar 18, movable radially of the cylinder and constantly pressed outwardly by coiled springs 19, for which seats 20 are formed in the bottom of the box. The bar 18 has guide-slots 60 21 to fit the cross-pins 16 and is also provided with recesses 22 to accommodate the heads of screws 14, it being understood that the bar 18 bears directly against the blade 13. 65 The cheek-block 18 pinches the web 3 against

the cylinder 1 in the usual manner. It is usually made in four sections placed end to end like the knife-sections.

The knife-bar 12 is extended at 23 to overhang the end of the cylinder 2 and provided 70 with a roller-stud 24, which runs in a groove 25, formed upon the periphery of a hollow boss 26, secured by bolts 27 to the side 7 of the frame. At its top the groove is formed with an oblique cam-surface 28, the engagement of the roller 24 with which during the rotation of the cylinder forces the knife-bar 12 to move endwise along the cylinder, this movement of the knife-bar being simultaneous 75 with the puncturing of the web by the teeth 15, because of their projection from the cylinder, so that the movement of the teeth with reference to the web is oblique, so that a longer incision is made by each tooth in the paper than would be the case if the tooth 80 were fixed upon the cylinder and penetrated the paper to the same extent. The portion of the incision due to the longitudinal movement of the tooth is seen at 29, Fig. 10, and this portion, taken with the portion due 85 strictly to the penetration of the tooth, equal the puncture 30, made heretofore by causing the entire body of the tooth to penetrate the paper. Each tooth 15 therefore makes an incision greater than the width of 90 the tooth at its intersection with the web, and these incisions taken together completely sever the web. Preferably, the length of the stroke of the knife-bar is a little greater than the pitch of the cutting-teeth. The return 95 stroke of the knife-bar is effected, preferably, after the cut is completed by a cam-surface 100 31, formed in said groove 25. The movements of the teeth may, however, vary or be otherwise effected within the scope of the invention. 105

In the usual channels 32, provided upon the cylinder 1, is provided a wooden bar 33, having a rubber facing 34, having a groove 35 to receive the tips of the teeth, and since 110 the latter penetrate the groove only slightly the sides of the latter run almost in contact with the teeth, and hence afford a support for the web during the severing operation, with the advantages already explained. The 115 upper part of Fig. 11 shows for comparison the usual projection of the entire body of the teeth into the groove and the consequent great width of the latter.

During the cutting operation the knife-bar 120 is moved to the left, as seen at Fig. 7, so that the inclined or oblique edges 36 of the teeth are advanced longitudinally of the paper, and owing to the length of the stroke, which is preferably slightly in excess of that necessary 125 to cause the incisions to join one another, a clean or smooth cut is produced across the web.

It will be observed that during the cutting 130 operation the teeth never project beyond the

surface of the cutter cylinder or roll a distance greater than the height of the teeth, so that without a longitudinal movement of the knife at the cutting operation only a series of 5 separate perforations would be formed.

Having thus described my invention, I claim—

1. In a mechanism for severing a web into sheets, the combination with a pair of revolving cylinders between which the web runs, of a cutting-blade having teeth and extending along one of said cylinders, said blade so mounted that the teeth are incapable of projecting from the surface of the blade-cylinder, 10 during the severing operation, a distance greater than the height of the teeth, and means for moving the blade endwise independently of its cylinder when it is in position to coact with the other cylinder in severing the paper.

2. In combination, a pair of revolving cylinders, a cutting-blade having teeth and extending along one of said cylinders, said blade so mounted that the teeth are incapable of projecting from the surface of the blade - cylinder, during the severing operation, a distance greater than the height of the teeth, and means for causing the teeth to penetrate the web in a single direction diagonal to the length of the blade throughout the web-severing operation.

3. In combination, a pair of revolving cylinders, a cutting-blade having teeth and extending along one of said cylinders, said blade so mounted that the teeth are incapable of such projection from the cylinder during the cutting operation that their punctures will unite to form a single continuous cut across the web, means for moving the 35 blade endwise during the entire web-cutting operation, and means for returning the blade to normal endwise position.

4. In combination, a pair of revolving cylinders, a series of cutting - teeth extending 40 along one of said cylinders and each having an inclined cutting edge, means for advancing said teeth longitudinally of the cylinder with their inclined edges foremost during the web-penetrating movement of the teeth, and independently of their cylinder, and means for 45 retracting the teeth.

5. In combination, a pair of revolving cylinders, a series of cutting - teeth extending along one of said cylinders, a coöperating bar 50 in the other of said cylinders, said bar having a longitudinal recess, the width of which does not substantially exceed the thickness of the teeth, the latter being so mounted as to be incapable during the web-cutting operation of 55 projecting into said recess so far that their punctures would unite to form a continuous cut across the web, means for moving the teeth longitudinally of their cylinder during the web-severing operation, so as to form

their punctures into a continuous cut, and 65 means for returning the teeth to original position.

6. The combination of a revolving cylinder, a bar parallel with the axis of the cylinder and extending along the same and mounted 70 for movement parallel with said axis, a toothed cutting-blade detachably secured to said bar, a bearing, means upon said bar to engage said bearing to effect such endwise movement of the bar during the web-punc- 75 turing operation of the teeth, and a coöperating cylinder.

7. A paper-cutting device comprising a box, a knife-bar movably mounted therein, knives with teeth thereon, each tooth having 80 an inclined cutting edge, and mechanism for giving the knives an oblique edgewise movement, with said inclined edges foremost, relatively to the paper, during the entire paper-cutting operation.

8. The combination of a revolving cylinder, a bar extending along the same and mounted for movement endwise of the cylinder, a series of blade-sections detachably secured upon said bar end to end and having 90 cutting-teeth with inclined edges, a fixed peripheral cam-groove concentric with the cylinder-axis, a stud upon said bar running in said groove, to effect reciprocation of the bar, and a coöperating cylinder.

9. A paper-cutting device, comprising a box, a knife-bar, knives with teeth thereon, a stud fastened to said knife - bar, cheek or guide blocks, and guide-pins for said cheek or guide blocks and knife-bar.

10. A paper-cutting device, comprising a box or casing, a knife-bar mounted therein, knives with teeth fastened to said knife-bar, cheek or guide blocks, springs for said cheek or guide blocks, means for moving the knife-bar, and pins for guiding the knife-bar.

11. The combination with a pair of revolving cylinders between which the web runs, of a serrated cutting-blade extending along one of said cylinders, but so mounted as to be incapable of punching slits of sufficient length to make a complete severance of the web, and means for moving said knife endwise during the slitting operation, sufficiently to merge the slits into a single cut, completely 110 severing the web, means being provided for so guiding said blade that its serrations or teeth do not project beyond the surface of its cylinder a distance greater than the height of 115 said teeth, during the slitting operation.

12. In combination, a pair of revolving cylinders, a projecting serrated cutting-blade extending along one of said cylinders, but capable of making only a partial severance of the web by reason of its projection from its 120 cylinder, and means for moving the blade parallel with the axis of its cylinder during the entire time in which the blade is in con- 125

tact with the web until the latter is completely severed, and means for returning the blade to normal endwise position.

13. In combination, a pair of revolving cylinders, a series of cutting-teeth extending along one of said cylinders and each having an inclined cutting edge, said teeth projecting from their cylinder only enough to effect a partial severance of the web, and means for advancing said teeth with their inclined edges foremost during the penetration of the web by the teeth, so as to effect a complete severance of the web.

14. In combination, a pair of revolving cylinders, a series of cutting-teeth extending along one of said cylinders, a coöperating bar in the other of said cylinders, said bar having a longitudinal recess which is about equal in width to the thickness of the teeth, and the latter being so mounted that their tips barely project into said recess during the revolution of the cylinders, so as to be capable by reason of such projection to effect only partial severance of the web, and means for moving the

teeth longitudinally of their cylinder during the penetration of the web by the teeth, so as to enlarge the punches into a continuous cut, thereby completely severing the web; means being provided for returning the teeth to original position.

15. A web-severing cylinder or carrier provided with a set of cutting-teeth, means co-operating with said teeth to enable the latter to penetrate the web, the construction and arrangement being such that the web is only partially severed by the penetration of the teeth, and means for moving the teeth in a direction substantially parallel with the cylinder-axis during their action upon the web, so as to merge their incisions into a continuous cut completely severing the web; means being provided for returning the teeth to normal position.
